UNITED STATES PATENT OFFICE.

LOUIS W. WRIGHT, OF NEW HAVEN, CONNECTICUT, ASSIGNOR TO THE W. & E. T. FITCH CO., OF NEW HAVEN, CONNECTICUT, A CORPORATION.

BUCKLE.

1,030,632.

Specification of Letters Patent. Patented June 25, 1912.

Application filed July 3, 1911. Serial No. 636,741.

To all whom it may concern:

Be it known that I, LOUIS W. WRIGHT, a citizen of the United States, residing at New Haven, in the county of New Haven and 5 State of Connecticut, have invented a new and useful Improvement in Buckles; and I do hereby declare the following, when taken in connection with the accompanying drawings and the letters of reference marked 10 thereon, to be a full, clear, and exact description of the same, and which said drawings constitute part of this specification, and represent, in—

Figure 1 a top or plan view of a buckle constructed in accordance with my invention. Fig. 2 a front end view of the same. Fig. 3 a perspective view of the slide detached. Fig. 4 a sectional view showing the strap attached to a buckle and the free end 20 ready to be engaged by the buckle. Fig. 5 a similar view showing the strap engaged by the buckle.

This invention relates to an improvement in buckles of the type known as slide buckles, 25 and particularly for buckles for use on book straps, skate straps or any other purposes for which a buckle may be used, the object of the invention being a simple arrangement of parts in which the frame may be cast and 30 the slide struck up from sheet metal, and a buckle complete in two parts; and the invention consists in the construction herein-after described and particularly recited in the claim.

35 In carrying out my invention, I employ a frame comprising side bars 2, 3, front bar 4 and rear bar 5, which rear bar, if desired, may be raised above the plane of the front bar to form a tuck loop. As clearly shown 40 in Fig. 2 of the drawings, the central portion of the under face of the front bar 4 is thickened to form a support 6 for the purpose as will hereinafter appear. The sides of the frame are connected near their rear 45 end by a strap bar 7 and by what I will term a lower bar 8 and upper bar 9. The plane of the upper face of the lower bar 8 is slightly below the lower face of the upper bar 9 so that a slide 10 may pass between 50 them. This slide is struck up from sheet

metal and is formed at its outer end with ears 11 which not only form stops to limit the movement of the slide but which provide sufficient width of material to form the transverse slot 12. The outer end or bar 13 55 of the slide is bowed corresponding to the under face of the bar 4 of the frame and so as to fit against it as shown in Fig. 2. It is desirable that the outer end of the slide be bent to provide a bearing for the strap and 60 the central portion of the under face of the bar 4 is thickened to form a support for this bowed portion of the slide so as to prevent the possibility of the slide becoming flattened. The slide is passed from front to 65 rear over the lower bar 8 and beneath the upper bar 9, and the rear end or tail 14 of the slide is turned at right angles upward in rear of the upper bar 9. This bend may be made before the slide is inserted and sufficient space arranged between the upper face 70 of the bar 8 and the lower face of the bar 9 to permit this tail to pass between them, after which the bar 9 may be slightly depressed so as to prevent the withdrawal of 75 the slide, or the slide may be inserted before the rear end is bent and this end turned upward in rear of the bar 9.

Instead of providing a strap bar 7 the strap may be connected to the rear bar of the 80 frame.

In use one end 17 of the strap is secured to the strap bar 7 or to the rear bar 5 of the frame, while the free end 18 is passed upward through the slot 12 in the slide and in 85 rear of the front bar 4. Tension being applied to the strap will force the slide forward and the strap will be engaged between the rear wall of the slot 12 and the edge of the bar 4. 90

I claim:—

A slide buckle comprising a frame having side bars, a front bar, a rear bar, an upper transverse bar and a lower transverse bar, the central portion of the under face of the 95 front bar made thicker than at the ends forming a support, a slide formed in its outer end with a slot and having the outer bar of the slot transversely bowed corresponding to the support on the under face 100

of the front bar, said slide passed beneath the front bar over the lower bar and under the upper bar, the inner end of the slide turned upward in rear of the said upper bar 5 with which it is adapted to engage to interlock the slide with the frame and to limit the outward movement of the slide.

In testimony whereof, I have signed this specification in the presence of two subscribing witnesses.

LOUIS W. WRIGHT.
